UNITED STATES PATENT OFFICE

ELMER E. GREENE, OF ALTOONA, PENNSYLVANIA

WEATHERSTRIP

Application filed November 11, 1929. Serial No. 406,376.

This invention appertains to new and useful improvements in window weatherstripping and more particularly to means of this character especially adapted for use in conjunction with railway car windows.

The principal object of this invention is to provide a weatherstrip which will effectively serve to exclude weather and also prevent rattling of the window.

Another important object of the invention is to provide a weatherstrip of the character described, which will permit the more easy actuation of the window due to the anti-frictional nature thereof.

During the course of the following specification and claim, various other objects and advantages of the invention will become apparent.

In the drawings;

Figure 1 represents a fragmentary horizontal sectional view through a window frame, sash and the novel weatherstripping structure.

Figure 2 represents a fragmentary perspective view of the guide for the sash.

Figure 3 represents a fragmentary perspective view of the spring weatherstrip.

By referring to the drawings, it will be seen that like numerals represent like parts as described hereinafter. Numeral 5 represents the usual stile portion of a metallic car window frame, the same being bent inwardly as at 6, outwardly as at 7, and then backwardly in parallel relation with respect to the portion 6 as at 8, to abut the outside car plate 9 as at 10. The opposite longitudinal edge portion of the stile is bent outwardly as at 11 and against the inner wall 12 of the car as at 13.

Numeral 14 represents the usual curtain guide, which is channeled in the manner denoted by numeral 15. The intermediate portion of the stile is usually bulged outwardly as at 16 throughout its longitudinal extent to partly receive the guide 14, which guide is secured to this bulged portion of the stile by suitable screws 17. The space between the guides 14 and the inwardly disposed portion 6 of the stile serves as a guideway for the window sash, although the guide is bevelled

as at 15' for cooperation with the latch generally referred to by numeral 34. The window sash frame is denoted by numeral 18 and is suitably reduced at its inner edge portion to accommodate the transparent pane 19, which pane is usually secured to the frame by some form of molding 20.

The outer vertical edge portions of the frame 18 are channeled as at 21 to receive the metallic guide, which in Figure 2 is generally referred to by numeral 22. This guide consists of an elongated sheet of metal bent to provide a trough 23 and a laterally disposed flange 24, which flange is provided with a suitable number of openings 25 through which securing means 26 may be disposed for securing the same guide to the frame 18.

The frame is not only channeled to receive the trough 23, but is also reduced at its front side to accommodate the flange 24, so that the outer surface thereof will be substantially flush with the outer surface of the frame.

The spring weatherstrip is generally referred to in Figure 3 by the numeral 27 and consists of a plate 28 bent laterally at one end portion as denoted by numeral 29 for disposition between the bulged portion 16 of the window frame stile and the aforementioned guide 14, as in the manner shown in Figure 1. The intermediacy of the plate 28 is disposed spacedly between the sash frame 18 and the intermediacy of the frame stile 5.

The opposite edge portion of the sheet is bent laterally as at 30 and inwardly as at 31, the bent portions 32 being cylindrical in the manner shown in Figure 3. The free edge portion of the portion 31 is constructed to provide a longitudinally extending rib 33 for tensional engagement within the trough 23, as in the manner clearly shown in Figure 1.

It will be observed that the intermediacy of the sheet 28 as well as the portion 30 will lie flatly against the intermediacy of the stile 5 and the portion 6 thereof respectively as in the manner shown in Figure 1. The cylindrical sprung portion 32 will project beyond the inner edge of the portion 6 while the portions 31 of the sheet will obliquely traverse the space between the sash frame 18 and the portion 6 of the frame stile 5 so that its ridge

portion 33 will tensionally bear in the trough 23.

The aforementioned latch 34 comprises a

5 sleeve 35 secured to the sash 18 so that the bevelled head 36 of the bolt may engage the bevelled surface of the guide 14 in the manner shown in Figure 1. An elongated handle 37 projects through the sleeve 35 and a spring 38 serves to urge the bolt normally toward 10 the guide 14. It will thus be seen that the sash will always be tensioned in a direction toward the portion 6 of the window frame.

Preferably the trough structure in the weatherstrip is manufactured of brass or 15 some other anti-frictional metal, but while the foregoing description has specifically set forth the details of the invention, it is to be understood that various changes in the shape, size and materials may be resorted to without 20 departing from the spirit or scope of the invention as claimed hereinafter.

Having described the invention, what is claimed as new is:

In combination with a window frame having 25 a stile at each side thereof and a sash having a groove in each side edge of its outer face, a U-shaped strip snugly fitting in each groove and having a flange attached to the sash, a spring strip having one edge attached 30 to each side of the window frame with a part bent at right angles and contacting the inner face of the stile, said part being rolled to form a tubular bead which is located beyond the stile and an extension on the bead on the stile 35 engaging part of the strip having one edge connected with the bead forming part and its other edge bent into U-shape to fit in the U-shape part of the first strip, the said extension, the stile engaging part and the major 40 portion of the frame engaging part of the strip being of plain, flat construction.

In testimony whereof I affix my signature.
ELMER E. GREENE.
